United States Patent Office

Des. 173,562
Patented Nov. 30, 1954

173,562

MEDAL OR SIMILAR ARTICLE

Adolph Frankenthaler, New York, N. Y.

Application October 10, 1952, Serial No. 21,793

Term of patent 14 years

(Cl. D29—15)

Fig. 1.

Fig. 2.

To all whom it may concern:

Be it known, that Adolph Frankenthaler, a citizen of the United States of America, residing in New York, in the county of New York and State of New York, has invented a new, original, and ornamental design for a Medal or Similar Article, of which the following is a specification, reference being had to the accompanying drawing forming a part hereof.

Fig. 1 is a front elevational view of a medal or similar article showing my new design; and

Fig. 2 is a rear elevational view thereof.

The medal is of conventional thickness.

The dominant features of my design reside in those features shown in full lines and in the ornamentation on the medal as illustrated in Fig. 2 of the drawing.

I claim:

The ornamental design for a medal or similar article, as shown and described.
